4 Claims. (Cl. 260—240)

The present invention relates, in general, to organic chemistry, and, more particularly, to certain novel 5-nitro-furfurylidene-(1) derivatives and a unique process for producing the same via the reaction of 5-nitro-furfurol-(2) with 1-aminotetrahydro-1,4-thiazine-4,4-dioxide. Additionally, the invention involves the use of the novel compounds of the invention as anthelmintics of rather specific and unique activity as explained in greater detail hereinafter.

In general, the compounds of the invention may be represented by the following structural formula

wherein R represents hydrogen, from 1 to 4 lower (C_1-C_4) alkyl radicals, from 1 to 2 aralkyl radicals such as benzyl, or aryl radicals such as phenyl.

Preferably, the indicated reaction of the 1-aminotetrahydro-1,4-thiazine-dioxide with 5-nitro-furfurol is effected within an organic solvent medium in which both of the starting components are soluble, and in which the desired end-product is insoluble.

By reference to United States Patent No. 3,001,992 issued to Bellamy et al. on September 26, 1961, there are described certain 5-nitro-furfurylidene-(2)-amino compounds carrying heterocyclic substituents, but these compounds exhibit only trace-activity against trypanosomes, or none at all, and are moreover, extremely toxic. Comparative testing of the unique compounds of the invention with respect to both their effectiveness and toxicity readily demonstrates the advance achieved through

2

use of the compounds of the invention over known derivatives of somewhat similar chemical structure and similar direction of activity.

Thus, the compounds of the invention are distinguished by a low order of toxicity and high activity against *Trypanosoma cruzi*, the causative agent for the Chagas' disease as well as other protozoa, e.g., *Trypanosoma congoense* and *Trypanosoma brucei*. In the former connection, for indications against the Chagas' disease (the South American form of trypanosomiasis, for example, the semicarbazide of 5-nitro-furfurol-(2) has been used heretofore.

In connection with the aforementioned comparative studies, the compounds of the invention were investigated with white mice. The animals were injected with *Trypanosoma cruzi*, and thereafter treated subcutaneously with the unit dosages indicated in Table I on four successive days, commencing one day after initial injection. For evaluation purposes, blood samples of the treated animals were examined microscopically for *Trypanosoma cruzi* at intervals of one day, commencing the sixth day after initial injection, and compared with untreated injected control animals of the same species.

As represented by the tabulated results, if the animals are treated with an insufficient dosage of the anthelmintics of the invention, the same number of trypanosomes are found in the blood as in that of the control animals (ϕ designates no effect). If, on the other hand, effective doses of the preparation are administered to the animals, the blood is free of trypanosomes for a few days or even for weeks. With reference to Table I, the ultimate test result is indicated by the designation "HE" (healing effect), provided the *Trypanosoma cruzi* cannot be detected within the peripheral blood of the test animals for four weeks or longer, and a re-infection takes a positive course. The designation "RE" (recidivation effect) indicates a recurrence of trypanosomes in the blood of the treated animals following a temporary negative microscopic examination of more than two days. The designation "T" (traces of effect) indicates an influence on the infection which could still be detected. The results of the tabulated studies were confirmed on additional strains of *Trypanosoma cruzi* of various origin.

TABLE I

Compound	Activity against <i>Trypanosoma cruzi</i> (mg./kg.) (subcutaneously) ³							Toxicity ¹ (mg./kg.) (subcutaneously)				
	500	250	100	50	25	10	5	2,000	1,000	500	250	100
	-----	E ⁴	RE	RE	RE-T	φ	-----	-----	-----	2/3	1/3	0/3
	-----	E ⁴	HE	RE	RE	RE	φ	3/3	0/3	0/3	0/3	-----
	-----	T	T	-----	-----	-----	-----	3/3	2/3	0/3	-----	-----
	-----	HE	RE	RE	RE	φ	-----	0/3	0/3	0/3	-----	-----
	-----	HE	RE	RE	RE	φ	-----	0/3	0/3	0/3	0/3	-----

HE: Healing effect.

RE: Recidivation effect.

T: Traces of effect.

φ: No effect.

¹ With a single treatment.

² Number of animals destroyed to total number of animals used.

³ Four treatments.

⁴ Toxic dose; four subcutaneous applications on successive days.

It is believed that the invention may be best understood by reference to the following specific examples illustrating the application of the foregoing principles and procedures in the production of typical compounds of the invention:

Example I

Fifteen (15) grams of 1-amino-tetrahydro-1,4-thiazine-4,4-dioxide were treated within 150 milliliters of acetic acid with 14.1 grams of 5-nitro-furfurol-(2), and the mixture heated for a short time. Orange-red crystals of 1-(5-nitro-furfurylidene-amino)-1,4-tetrahydrothiazine-4,4-dioxide separated out at once which, following filtration via suction and washing with water, were immediately found to be analytically pure. The melting point, following recrystallization from acetic acid, was found to be 191° C.

Analysis.—(C₉H₁₁N₃O₅S): Molecular weight, 273. Calculated: C, 39.6%; H, 4.03%; N, 15.4%. Found: C, 39.6%; H, 4.25%; N, 15.4%.

Example II

1 - amino - 2-methyl-tetrahydro-1,4-hydroxythiazine-4,4-dioxide, in amount of 15.4 grams, was dissolved in 100 milliliters of alcohol and 5 milliliters of acetic acid, and then added to a solution consisting of 14.1 grams of 5-nitro-furfurol-(2) within 100 milliliters of alcohol. The resultant mixture was heated for a brief period of time and then cooled for crystallization. Twenty-eight (28) grams of orange-red crystals of 1-(5-nitrofurfurylidene-amino)-tetrahydro-2-methyl-1,4-thiazine-4,4-dioxide separated out of the reaction mixture. The melting point, following recrystallization from dilute acetic acid, was found to be 172° C.

Analysis.—(C₁₀H₁₃N₃O₅S): Molecular weight, 287. Calculated: C, 41.8%; H, 4.53%; N, 14.7%. Found: C, 41.92%; H, 4.66%; N, 14.9%.

The production of the 1-amino-2-methyl-tetrahydro-1,4-hydroxythiazine-dioxide used as the starting compound in the foregoing synthesis can be effected by (a) reacting 2-mercaptopropanol with propylene oxide in the presence of potassium hydroxide. 2-hydroxyethyl-2-hydroxypropyl sulphide of boiling point 160° C. at 15 mm. Hg is thus obtained; (b) distillation of 2-hydroxyethyl-2-hydroxypropyl sulphide over p-toluene-sulphonic acid or potassium hydrogen sulphate under normal pressure. 2-methyl-1,4-hydroxythiane is thus obtained (boiling point= 45-46° C. at 18 mm. Hg; $n_D^{20}=1.4942$); (c) oxidation of 2-methyl-1,4-hydroxythiane with hydrogen peroxide in acetic acid to form 2-methyl-1,4-tetrahydro-thioxane-4,4-dioxide (melting point 82° C. following recrystallization from alcohol/ether).

Analysis.—(C₈H₁₀O₃S): Molecular weight, 150. Calculated: S, 21.3%. Found: S, 21.8%; or (d) reacting 2-methyl-1,4-tetrahydro-thioxane-4,4-dioxide with hydra-

zine at 180° C. with the use of an excess of hydrazine, leading to 1-amino-2-methyl-1,4-tetrahydro-thiazine-4,4-dioxide (melting point=115° C.).

Analysis.—(C₅H₁₂N₂O₂S): Molecular weight, 164. Calculated: C, 36.6%; H, 7.32%; N, 17.1%. Found: C, 36.4%; H, 7.31%; N, 16.9%.

Example III

5-nitro-furfurol-(2), in amount of 14.1 grams, was dissolved within 100 milliliters of alcohol and then added to a solution of 23 grams of 1-amino-2-ethyl-tetrahydro-1,4-thiazine-4,4-dioxide (78%: determined by titration with 1/10 N iodine solution in a sodium bicarbonate alkaline/alcoholic solution). The crude crystal mass was filtered-off with suction and recrystallized from dilute acetic acid (melting point=147-148° C.; red crystals).

Analysis.—(C₁₁H₁₅N₃O₅S): Molecular weight, 301. Calculated: C, 43.9%; H, 4.98%; N, 13.9%. Found: C, 43.7%; H, 5.25%; N, 13.9%.

The 1 - amino - 2-ethyl-tetrahydro-1,4-thiazine-4,4-dioxide used as the starting compound in the foregoing synthesis may be obtained in a manner analogous to that described above in connection with Example II, (a)-(d), namely:

- (a) 2 - hydroxyethyl - 2 - hydroxybutyl sulphide (boiling point: 164-165° C. at 18 mm. Hg; $n_D^{20}=1.5058$);
- (b) 2-ethyl-thioxane-(4,1) (boiling point: 55-60° C. at 17 mm. Hg; $n_D^{20}=1.4968$), and
- (c) 2-ethyl-thioxane-(4,1)-dioxide-(4,4) (melting point: 51-54° C.).

What is claimed is:

1. A compound of the formula:

wherein R is a member selected from the group consisting of hydrogen, lower alkyl, benzyl and phenyl.

2. The chemical compound, 1-(5-nitro-furfurylidene-amino)-1,4-tetrahydrothiazine-4,4-dioxide.

3. The chemical compound, 1-(5-nitro-furfurylidene-amino)-tetrahydro-2-methyl-1,4-thiazine-4,4-dioxide.

4. The chemical compound, 1-(5-nitro-furfurylidene-amino)-tetrahydro-2-ethyl-1,4-thiazine-4,4-dioxide.
